UNITED STATES PATENT OFFICE.

ZACHARY T. COWART, OF ALAMEDA, CALIFORNIA.

ATTACHMENT FOR STOVES.

1,247,936.

Specification of Letters Patent. Patented Nov. 27, 1917.

Application filed September 11, 1916. Serial No. 119,597.

To all whom it may concern:

Be it known that I, ZACHARY T. COWART, a citizen of the United States, residing at Alameda, in the county of Alameda and State of California, have invented certain new and useful Improvements in Attachments for Stoves, of which the following is a specification.

This invention relates to an improved attachment for stoves, more particularly to a device for utilizing the waste heat around gas burners for heating water.

The principal object of my invention is to provide a device of this character, which may be attached to stoves already in use, that is simple in construction and efficient in accomplishing the object above set forth.

Another object of my invention is to so arrange the various parts that large or small cooking vessels may be supported upon the fuel burner, and a still further object is to so construct the parts that the maximum amount of waste heat is utilized without interfering with the use of the burner for cooking purposes.

With these and other objects in view the invention consists of certain novel features of construction, the combination and arrangement of parts herein illustrated and more specifically pointed out in the appended claims, reference being had to the drawings accompanying this specification.

Figure 1— is a view in plan of the attachment with a portion broken away showing the manner of mounting on the top of a stove.

Fig. 2— is a view in section on line 2—2 of Fig. 1.

Fig. 3— is a bottom plan view of a modified form of my invention.

Fig. 4— is a view in section on the line 4—4 of Fig. 3.

Referring to corresponding parts of the several views by the same numerals of reference 1 denotes the top portion of the stove around the inner edge of which is a ledge 2 on which the grid or top plates are normally supported.

When my invention is used this grid is removed and a plate 3 is substituted therefor. This plate is arranged to fit within the ledge 2 and is provided with a rib 4 to prevent matter which may be spilled thereon from flowing down the sides.

In the preferred embodiment of my invention I provide openings 5 in the top of

plate 3 which are disposed centrally over the burners 6. These openings are provided with a ledge 7 adapted to hold a close fitting lid 8 so that when not used for cooking purposes the various openings are closed by these lids and the heat retained under the plate. Embracing each of the burners 6 is a ring 9, having an annular chamber 10 connected with intake and outlet openings 11 and 12 respectively.

In one form of my invention I provide the ring 9 with the plurality of inwardly projecting hollow radial lugs 13 whereby a greater heating efficiency is secured. Extending inwardly from the ends of these lugs are fingers 14 which form a grille work on which small cooking utensils may be seated and which further serve to conduct the heat from the burner to the ring 9. I so construct the various parts that the top of fingers 14 are on alinement with the top of lugs 13, and occupy substantially the same level above the burners 6 as did the regular grids.

When a stove is equipped with several burners the rings 9 are connected together by means of nipples 15 to form a continuous cavity from one to the other. The first ring is connected to a pipe 16 leading from the bottom of a storage reservoir not shown, and the outlet of the last ring is connected by a pipe 17 to the top of the storage reservoir. The various rings are supported from the stove top 1 in any preferred manner such as by providing projecting arms 18 which rest on the ledge 2 or which are connected directly with the under side of plate 3, it being desirable that the rings as a whole have a slight pitch upward from the pipe 16 to the pipe 17.

In the modified form shown in Figs. 3 and 4 the ring 9 is cast as an integral part of the plate 3' the same form however being maintained.

If my device is to be applied to a gas stove the usual supporting grids are removed and one or more plates 3 provided which have the same size and shape as the grids of the gas stove and which are provided with openings positioned centrally above the burners. When one burner is lighted it will be apparent that the heat instead of escaping upwardly around the vessel above the burners will be maintained under the plate and will form a heated atmosphere the entire length thereof. By this

means the top of the plate will be heated to a certain degree together with the various rings 9, thus other portions of the plate may be used for slow cooking while the water 5 within the rings 9 will be heated and circulated toward pipe 17 into the storage reservoir.

While I have shown the preferred construction of my invention it will be understood that minor changes may be made in details of design and form of the heating rings and these also I wish to include within the scope of the claims.

I claim as new and wish to cover by Letters Patent:—

1. A top for gas stoves comprising a flat supporting plate having openings concentrically disposed above the stove burners, hollow annular rings around said openings 20 on the under side of said plate, lugs extend-

ing inwardly from said rings and having cavities connecting with the hollow of said rings, fingers forming on the inner ends of said lugs, the top of said lugs and said fingers being in alinement and below the top 25 of said plate.

2. A top for gas stoves comprising a flat supporting plate having openings concentrically disposed above the stove burners, integrally formed hollow annular rings 30 around said openings on the under side of said plate and substantially embracing the stove burners, lugs extending inwardly from said rings and having cavities connecting with the hollow of said rings, fingers 35 forming on the inner ends of said lugs, the top of said lugs and said fingers being in alinement and below the top of said plate.

In testimony whereof I affix my signature.
ZACHARY T. COWART.

Copies of this patent may be obtained for five cents each, by addressing the "Commissioner of Patents, Washington, D. C."
